UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

TYPOGRAPHICAL LINE-CASTING MACHINE.

1,058,321.

Specification of Letters Patent.

Patented Apr. 8, 1913.

Application filed September 21, 1910. Serial No. 583,051.

To all whom it may concern:

Be it known that I, CARL MUEHLEISEN, a citizen of the United States of America, residing at 88 Chausseestrasse, Berlin, N. 4, in 5 the Empire of Germany, have invented new and useful Improvements in Typographical Line-Casting Machines, of which the following is a specification.

This invention relates to improvements in 10 typographical line casting machines and particularly to the means whereby the knives used for trimming the resultant cast lines, are adjusted for different body dimensions through the intermediary of the wheel carriage upon which are mounted the line-casting molds.

The said invention is an improvement or 20 modification of that for which a patent was granted under No. 941,384 on November 30th 1909. According to that patent the apparatus was so constructed that the mold wheel or carrier effected the movement of the adjustable knife in only one direction, while a spring or springs moved it in the 25 opposite direction; the object of the present invention is to so construct the said apparatus that the mold wheel or carrier shall effect or control the adjustment of the movable knife both toward and away from the 30 companion or relatively fixed knife.

The invention will be best understood by 35 reference to the accompanying drawings in which, as an example, it is shown applied to appropriate parts of the machine known commercially under the trademark "Linotype."

In these drawings Figure 1 is a right-hand 40 side elevation showing the knife-block, and, in vertical section, a portion of the mold carrier; Fig. 2 is a rear elevation of the trimming knives and knife-block; Fig. 3 is a horizontal section taken about on the line 3-3 of Fig. 1, and with certain parts omitted; Fig. 4 is a front elevation of the 45 mold carrier, with two molds thereon of respectively different body dimensions; Fig. 5 is a view corresponding to Fig. 1, of a modified construction of the devices shown in that figure; Fig. 6 is a rear elevation of the adjustable knife and other adjacent parts, and Fig. 7 is a plan, partly in section, and Fig. 8 an elevation of detached parts of the apparatus shown in Figs. 5 and 6.

1 represents the fixed knife secured, as 50 ordinarily to the vise frame or other rela-

tively stationary part 2 (Fig. 3) of the machine frame; 3 represents the adjustable knife, horizontally guided on the knife block 4 in well-known manner so that it can be moved toward and away from the companion knife 1, and only thus. The knife-block 4, as ordinarily is detachably secured to the part 2.

5 is a spring (there are preferably two such springs) constantly tending to move 60 the adjustable knife 3 farther away from the fixed knife 1.

6 is the mold carrier which, as illustrated, takes the form of the well-known mold wheel; 7 and 8 are two molds secured to the 70 mold carrier 6, of respectively different body dimension.

All of the foregoing parts are common to 75 both of the constructions illustrated in the drawings.

With particular reference to the arrangement represented in Figs. 1, 2 and 3, 9 is a double stepped wedge having at each end, two surfaces 10, 11 situated in two different parallel vertical planes, the said surfaces 80 being connected by an inclined or curved surface 12, and the distance apart of the two said planes corresponding with the difference in the body dimensions of the two molds 7, 8. The surfaces 10, 11 are adapted 85 to coact with abutment screws 13 adjustable in the lugs 14 integral with the knife block 4.

15 is a pin fast to the wedge 9 and projecting from the right-hand side thereof, 16 90 is a three-armed lever pivoted on a stud 17 fast to the knife block, and the middle arm of which, by its forked end, engages with the pin 15. The upper and lower arms of the lever 16 are each pivoted to a cranked 95 rod 18 or 19 which, by a screw and slot 20, is guided on the side of the knife block 4. The rear ends of the rods 18, 19 extend into the forward path of the mold carrier, and adjacent to the two molds 7 and 8 there are 100 provided two recesses or holes 21, 22 adapted to freely receive the rearward ends of the rods 18, 19 respectively. The mold carrier 6 is also provided with the usual registering sockets or pins 23; these, however, 105 constitute no part of the present invention.

By the foregoing arrangement the wedge 9 must occupy its lower position when the mold 8 of the smaller body dimension is in use, and its higher position when the mold 110

7 of the larger body dimension is in use, and for this purpose the mold carrier 6 is adapted to correspondingly operate the two rods 18, 19. Thus, when the mold 7 is in use, the advance of the mold carrier 6 presents a solid part of the latter to the rod 18, and receives the rear end of the rod 19 in the hole 22, and in the reverse manner, when the mold 8 is in use, the advance of the mold carrier 6 presents a solid part of the latter to the rod 19 and receives the rear end of the rod 18 in the hole 21. Consequently, if the advancing mold carrier 6 finds either of the rods 18 or 19 projecting into its forward path at a part at which it is unprovided with a hole 21 or 22, that rod will be moved forward and the wedge 9 will be correspondingly raised or lowered.

When for the two molds 7 and 8 represented in Fig. 4, others are substituted for larger or smaller body dimension, but between which dimensions there is the same relative difference as in the substituted molds, the screws 13 can be adjusted to provide for such altered conditions, without changing the wedge 9, but when the two substituting molds have not the same relative difference of body dimension as the substituted molds, then a new wedge having the desired different step relationship, must be substituted for that last used in the machine.

The arrangement shown in Figs. 5 and 6 allows of the preliminary or manual knife adjustments for changes of body dimension being more readily effected than does that previously described, and without risk of disturbing the parallelism of the knives as is the case when the abutment screws 13 are turned. In this arrangement the wedge 9 is of the inclined type as distinguished from the stepped type shown in Fig. 2, and it has, as already well known in the art, two inclined surfaces, one at each end; it is connected with the three armed lever 16 in the same manner as that before described with reference to Fig. 1, but the said lever, as distinguished from that in the preceding example, is resiliently connected to the rods 18, 19. For this purpose each of the rods 18, 19 has a forwardly extending arm terminating in a hook 24 to which is attached one end of a spring 25 whose other end is attached to a pin 26 adjustably secured in the respective arm of the lever 16. This pin 26 penetrates a slot 27 in the respective rod 18 or 19 and terminates in a head 28 between which and a collar 29 the said rod is capable of sliding relatively to the pin 26 in the direction of the length of the slot 27, and only thus.

The rear ends of the rods 18, 19 of Figs. 5 and 6, are guided in lugs 30 integral with the knife block 4, and on the back of the wedge 9 are carried two vertical adjustable abutment screws 31 adapted to co-act with

two lugs 32 integral with the knife block 4, when the wedge reaches the respective terminal positions corresponding with the two terminal knife adjustments. Each of the pins 26 extends through a curved slot 33 in the respective arm of the lever 16, and it may, by a nut 34 or otherwise, be secured in different positions along the said slot according to whether the particular body dimensions to be provided for, require the wedge 9 to be moved in a higher or lower zone.

In the operation of the last described device, the inward and outward movement of the knife 3 relatively to the companion knife 1 (which latter is not represented in Figs. 5 and 6) is arrested at the instant at which it is at the pre-determined distance from the said companion knife, by the respective screw 31 abutting against the corresponding lug 32, and if at that instant the mold carrier 6 had not yet reached its foremost position, it, by its further forward motion, moves the appropriate rod 18 or 19 still farther forward, this excess of motion of the rod, however, has no effect on the lever 16 and results merely in the elongation of the respective spring 25 which, on the retraction of the mold carrier 6, contracts to its original length.

For adjusting the last described devices to suit molds of other body dimensions than those indicated, the simplest method is to remove the wedge 9 then in the machine, together with its abutment screws 31, and substitute therefor another wedge with its abutment screws so adjusted as to permit of the said wedge being operated in a different zone from that appertaining to the substituted wedge. Or, the wedge may have its screws 31 adjusted without its position on the machine being disturbed.

In respects other than those just particularized, the operation of the devices shown in Figs. 5 and 6 is practically the same as that before described with reference to Figs. 1, 2, 3 and 4.

It will be observed that the only essential requirement in carrying my invention into effect is to have for each mold means to effect a positive actuation in both directions of the knife adjusting means, and while it is preferred to have the surfaces by which the adjusting devices are actuated on the mold carrier, it will of course be understood that these surfaces may be on the mold themselves or located elsewhere, as may be most convenient.

Having described my invention, what I claim and desire to secure by Letters Patent is:-

1. In a typographical line casting machine, the combination with two parallel trimming knives and knife adjusting devices in operative relationship to one of them, of a

- mold carrier adapted to operate positively the knife adjusting means in the directions necessary for both increasing and decreasing the distance between the knives.
- 5 2. In a typographical line casting machine, the combination with two parallel trimming knives, means exerting a constant tendency to move one of the knives relatively to the other, to vary the distance between them, and a wedge adapted to act on the said knife in opposition to the said means, of a mold carrier adapted to move positively the wedge longitudinally in relatively opposite directions.
- 10 3. In a typographical line casting machine, the combination of two parallel trimming knives, a wedge adapted to act on one of the knives to move it relatively to the companion knife, with a mold carrier adapted to move positively the wedge longitudinally in relatively opposite directions.
- 15 4. In a typographical line casting machine the combination with two parallel trimming knives, a spring exerting a constant tendency to move one of the knives away from the other, and a wedge longitudinally movable to move the spring-pressed knife toward the other one and to allow the spring to move it away from the said other one, of a mold carrier adapted to move positively the wedge longitudinally in relatively opposite directions.
- 20 5. In a typographical line casting machine, the combination with two parallel trimming knives, and a wedge adapted to act on one of the knives to move it relatively to the companion knife, of two rods operatively connected with the wedge adapted to move it in respectively opposite directions, and a reciprocable mold carrier, adapted to move each of the rods alternately in one direction while the other of such rods is moved in the opposite direction.
- 25 6. In a typographical line casting machine, the combination with two parallel trimming knives, and a wedge adapted to act on one of the knives to move it relatively to the companion knife, of a lever operatively connected with the wedge to move it longitudinally, two rods operatively connected to the lever adapted to rock it in respectively opposite directions, and a reciprocable mold carrier, adapted to move each of the rods alternately in one direction while the other of such rods is moved in the opposite direction.
- 30 7. In a typographical line casting machine, the combination of two parallel trimming knives, a wedge adapted to act on one of the knives to move it relatively to the companion knife, a lever operatively connected with the wedge to move it longitudinally, two rods adapted to rock the lever in respectively opposite directions, resilient means connecting the rods with the lever,
- 35 and a reciprocable mold carrier, adapted to move each of the rods alternately in one direction while the other of such rods is moved in the opposite direction.
- 40 8. In a typographical line casting machine, the combination of two parallel trimming knives, a wedge adapted to act on one of the knives to move it relatively to the companion knife, a lever operatively connected with the wedge to move it longitudinally, two rods adapted to rock the lever in respectively opposite directions, resilient means connecting the rods with the lever, a reciprocable mold carrier, adapted to move each of the rods alternately in one direction while the other of such rods is moved in the opposite direction, and abutment devices adapted to stop the wedge at the respective ends of its travel.
- 45 9. In a typographical line casting machine, the combination of two parallel trimming knives, a wedge adapted to act on one of the knives to move it relatively to the companion knife, adjustable abutments adapted to bear on the said wedge, a lever operatively connected with the wedge to move it longitudinally, two rods operatively connected with the lever and adapted to rock it in respectively opposite directions, and a reciprocable mold carrier, adapted to move each of the rods alternately in one direction while the other of such rods is moved in the opposite direction.
- 50 10. In a typographical line casting machine, the combination of two parallel trimming knives, a wedge adapted to act on one of the knives to move it relatively to the companion knife, a surface on the wedge being inclined to the direction of the wedge's longitudinal motion, an abutment bearing on the said surface to move the wedge laterally, a lever operatively connected with the wedge to move it longitudinally, two rods operatively connected with the lever and adapted to rock it in respectively opposite directions, a reciprocable mold carrier, adapted to move each of the rods alternately in one direction while the other of such rods is moved in the opposite direction, and adjustable abutment devices adapted to stop the wedge at the respective ends of its travel.
- 55 11. In a typographical line casting machine, the combination of two parallel trimming knives, a wedge adapted to act on one of the knives to move it relatively to the companion knife, a surface on the wedge being inclined to the direction of the wedge's longitudinal motion, an adjustable abutment bearing on the said surface to move the wedge laterally, a lever operatively connected with the wedge to move it longitudinally, two rods adapted to rock the lever in respectively opposite directions, resilient means connecting the rods with the lever,

a reciprocable mold carrier, adapted to move each of the rods alternately in one direction while the other of such rods is moved in the opposite direction, and adjustable abutment devices adapted to stop the wedge at the respective ends of its travel.

12. In a typographical line casting machine, the combination of two variant molds, two parallel knives to trim the slugs delivered from said molds, and means for adjusting one knife in one direction or the

other, with automatic means for positively actuating the said adjusting means in both directions according to the size of the mold presented opposite the knives.

15

In witness whereof I have hereunto set my hand in the presence of two witnesses.

CARL MUEHLEISEN.
